UNITED STATES PATENT OFFICE

162,808

STOCKING

Allen Erwin Gant, Glen Raven, N. C.

Application July 31, 1950, Serial No. 11,498

Term of patent 3½ years

(Cl. D47—7)

To all whom it may concern:

Be it known that I, Allen Erwin Gant, a citizen of the United States, residing at Glen Raven, in the county of Alamance and State of North Carolina, have invented a new, original, and ornamental Design for Stockings, of which the following is a specification, reference being had to the accompanying drawing, forming a part hereof.

The single figure is a side view of a stocking showing my new design.

I claim:

The ornamental design for a stocking, as shown.

ALLEN ERWIN GANT.
